UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

ELECTRIC WAVE FILTER.

Application filed December 31, 1920. Serial No. 434,388.

This invention relates to electric wave filters adapted to be employed in a line such as a telephone line, to prevent the passage of currents of certain frequencies and permit 5 the passage of currents having other frequencies.

It has for its object to produce filters of various types which have the characteristics of types of filters in general already known, 10 but which may be manufactured from a less amount of material, thus reducing the cost and size of the filter.

In accordance with the invention, filter sections are employed which have similar 15 impedances spaced apart in the direction of current propagation but having mutual impedance therebetween, and which have one or more impedances located between the mutually related impedances. The effect of mutual impedance in general is to add an impedance to the common portion without the use of additional apparatus.

The invention will be more fully understood from the following detailed description 25 and claims, taken in connection with the accompanying drawings in which Fig. 1 represents schematically, a filter section embodying the invention, Figs. 2, 3 and 4 represent modified forms of the invention.

30 Fig. 5 represents a filter having a plurality of sections of the type shown in Fig. 2; Fig. 6 represents a filter without mutual inductance which is electrically the equivalent of Fig. 5, and Figs. 7 and 8 represent filter sections 35 which are the equivalents of Figs. 1 and 4 respectively.

In Fig. 1 is shown a filter section having a shunt condenser C_2 and series of impedances each comprising a condenser C_1 , and an inductance L_1 in parallel. The inductances L_1 are wound in series opposing relation on the core 8. By series opposing relation is meant that relation in which the coils are connected in series in such a direction that the flux 45 produced by the current in one coil is opposed or decreased by that produced by the current flowing in the other coil. This results in a transformer action and as is well known, is equivalent to the insertion of an additional self inductance in a branch common to the two meshes. This equivalent in-

ductance is shown at M_1 in Fig. 7. The inductance due to magnetic leakage remains as shown at $L_1 - M_1$ in Fig. 7.

Fig. 1 may be regarded as a general case 55 of which Fig. 2 is a specific form having only inductance in its series arms. If L denotes the self-impedance of each winding, M the mutual impedance, and C the impedance of the shunt condenser in a section of the filter shown in Figs. 2 and 5, and if the impedances in Fig. 6 have the values indicated on the drawing, it can be shown by Kirchhoff's laws that a section of the former is equivalent to a section of the latter. Assume 65 that equal electromotive forces E are applied to the left hand side of the first section in Figs. 5 and 6, and that the first sections are short-circuited at midseries at the right. A mid-series termination is one 70 which includes one half of the series inductance of the terminal section. Designating the total current entering each filter as I_L and I_L' respectively, and the currents in the condensers by I_C and I_C' respectively, 75 then by Kirchhoff's second law, the currents in the short-circuited branch are $I_L - I_C$, and $I_L' - I_C'$ respectively. By Kirchhoff's first law we obtain from Fig. 5 by going around the first mesh:

$$E = I_L L - (I_L - I_C) M + I_C C,$$

or

$$E = I_L (L - M) + I_C (C + M), \quad (1)$$

and by going around the outer mesh:

$$E = I_L L - (I_L - I_C) M + (I_L - I_C) L - I_L M,$$

or

$$E = I_L (2L - 2M) - I_C (L - M) \quad (2)$$

In Fig. 6 by going around the first mesh we obtain:

$$E = I_L' (L - M) + I_C' (C + M) \quad (3)$$

and by going around the outer mesh:

$$E = I_L' (L - M) + (I_L' - I_C') (L - M)$$

or

$$E = I_L' (2L - 2M) - I_C' (L - M) \quad (4)$$

By comparison of equations (1) and (2)

with equations (3) and (4), it is evident that the currents in corresponding branches in Figs. 5 and 6 are equal.

The filter of Fig. 6 is a low pass filter of the form shown in Fig. 9 of the G. A. Campbell Patent No. 1,493,600, dated May 13, 1924. It was shown in G. A. Campbell patent No. 1,227,113, dated May 22, 1917, that a filter having a plurality of sections, each having a total series impedance Z_1 , between adjacent shunt arm and a shunt impedance Z_2 , will transmit a band of frequencies whose limits are determined by the equations:

$$15 \quad \frac{Z_1}{Z_2} = 0 \quad (5)$$

and

$$20 \quad \frac{Z_1}{Z_2} = -4 \quad (6)$$

In the filter of Fig. 6,

$$Z_1 = j2(L-M)\omega, \quad (7)$$

and

$$25 \quad Z_2 = j\left(M\omega - \frac{1}{C\omega}\right), \quad (8)$$

in which $j = \sqrt{-1}$, L and M represent inductance, C represents capacity; and $\omega = 2\pi f$, in which f represents frequency.

30 Combining (7) and (8),

$$\frac{Z_1}{Z_2} = \frac{2(L-M)\omega}{M\omega - \frac{1}{C\omega}} = \frac{2(L-M)C\omega^2}{MC\omega^2 - 1} \quad (9)$$

35 Assuming $\frac{Z_1}{Z_2} = 0$, we get from equation 9,

$$\omega = 0 \text{ or } f = 0$$

40 Assuming $\frac{Z_1}{Z_2} = -4$, we get

$$\omega = \frac{2}{\sqrt{2C(L+M)}}$$

45 or

$$f = \frac{1}{\pi\sqrt{2C(L+M)}} \quad (10)$$

Therefore, the filter of Fig. 6, and hence that of Fig. 5, also, will transmit freely all frequencies between 0 and

$$\frac{1}{\pi\sqrt{2C(L+M)}}$$

55 It was shown in Patent No. 1,227,113 above referred to that the propagation constant Γ of a filter of this type is determined by the equation:

$$60 \quad \Gamma = \cosh^{-1}\left(\frac{1}{2} \frac{Z_1}{Z_2} + 1\right) \quad (11)$$

This may be expressed:

$$65 \quad \Gamma = 2 \cosh^{-1} \sqrt{1 + \frac{1}{4} \frac{Z_1}{Z_2}} \quad (12)$$

Putting the value of $\frac{Z_1}{Z_2}$ from equation (9) in equation (12) we get

$$70 \quad \Gamma = 2 \cosh^{-1} \sqrt{\frac{LC\omega^2 + MC\omega^2 - 2}{2(MC\omega^2 - 1)}} \quad (13)$$

Since the quantity under the radical will be infinite when $MC\omega^2 = 1$, it is evident from equation (13), that the attenuation will be 75 a maximum when $MC\omega^2 = 1$, or

$$75 \quad f = \frac{1}{2\pi\sqrt{MC}} \quad (14)$$

This is the condition of resonance in the 80 shunt arm. If the frequency of resonance as determined by equation (14) be denoted by f_r , the cut-off frequency, as determined by equation (10), by f_c , and the ratio $\frac{f_r}{f_c}$ by a , 85 it will be seen that any desired sharpness of cut-off can be obtained by assigning a positive value to a more or less approaching unity.

90 If the core 8 be specially designed to be free from hysteresis and eddy currents there will be very little resistance effectively in the shunt arm of Fig. 2 as compared with that of a shunt arm of Fig. 6, since the latter contains the direct current resistance of the winding of inductance M. It follows that the maximum attenuation of a filter of the type shown in Figs. 2 and 5 can be made to approach more nearly infinity than that of Fig. 6.

95 In Fig. 3, is shown a convenient arrangement for varying the self-impedances and the mutual impedance of the windings in a filter section of the type shown in Fig. 2. The coils L_3 are wound on sleeves 10 and 11. Sleeve 10 may be mounted on a support (not shown) and sleeve 11 is pivotally connected to sleeve 10 as indicated at 12. Cores 14 and 15 are mounted for endwise movement in the sleeves 10 and 11. It is apparent that the magnetic leakage, and consequently the mutual inductance, may be varied by rotating the sleeve 11 about its pivot 12, and that the self-inductances may be varied by sliding the cores 14 and 15 in and out.

100 By methods similar to those used above in connection with Figs. 5 and 6, it can be shown that the sections shown in Figs. 1 and 4 are electrically equivalent to sections having the forms shown in Figs. 7 and 8 respectively. The characteristics of a filter having sections of the form of Figs. 4 or 8 are similar to those of the filter shown in Fig. 8 of the Campbell Patent No. 1,493,600, above referred to. That is, it is a high pass filter which may be given a sharp cut-off by making the frequency of resonance approach the frequency of cut-off.

105 What is claimed is:

1. An electrical network comprising a condenser, means for connecting said network between two sections of a circuit and an inductance between said condenser and each of said connections said inductances being so related as to have mutual inductance and being connected in series opposing relation. 60
2. An electrical network adapted to be connected between two sections of a circuit, said network comprising a shunt condenser, and an inductance at each side of said condenser, said inductances being so related as to have mutual inductance and being connected in series opposing relation. 65
3. An electrical network adapted to be connected between two sections of a circuit, said network comprising an impedance element, and an inductance at each side of said impedance element, said inductances being so related as to have mutual inductance so as to effectively add positive inductive reactance to the impedance element. 70
4. In a filter section having symmetrical halves connected in series with respect to current propagation and an inductance in each of said halves, said inductances being so related as to have mutual inductance and being connected in series opposing relation with respect to said current propagation, and an impedance element common to said halves. 75
5. In a filter section having symmetrical halves arranged in series with respect to current propagation, a series inductance in each of said halves, and shunt capacity common to said halves, said inductances being so related as to have mutual inductance which resonates with the shunt capacity at a frequency in the attenuated range. 80
6. A wave filter section having two pair of terminals for connection to a line or other filter sections, a shunt path comprising a condenser between said pairs of terminals, an inductance at each side of said shunt path having mutual inductance with the inductance at the opposite side, and being connected in series opposing relation therewith. 85
7. A filter section having two pairs of terminals for connection to a line or other filter sections, a shunt path comprising a condenser between said pairs of terminals, inductances at either side of said shunt path, an inductance at one side of said shunt path being wound on a common magnetic structure in series opposing relation with an inductance on the opposite side. 90
8. A wave filter comprising series inductances having mutual inductance therebetween, and a shunt capacity having a terminal connected between said inductances, whereby mutual inductance is effectively in series with said capacity, said elements having such relation to each other that the ratio of the frequency of resonance of the shunt path to the cut-off frequency of the filter closely approaches unity. 95
9. A wave filter comprising a plurality of reactive elements and a path for shunting out frequencies to be suppressed, one of said reactive elements having mutual reactance with an element electrically more distant from the source of currents, said reactive elements being so proportioned that the ratio of the frequency at which maximum suppression occurs to the frequency at which suppression begins closely approaches unity. 100
10. A wave filter comprising two inductive windings, a core for each of said windings, said cores being pivotally connected together. 105
11. A wave filter comprising two inductive windings, a core for each of said windings, said cores being mounted for relative movement to vary the mutual inductance of said windings. 110
12. A wave filter comprising two inductive windings, a core for each of said windings, said cores being mounted for relative movement to vary the mutual inductance of said windings, and for reciprocal movement in their respective windings. 115
13. A wave filter comprising a condenser and at least two inductive windings having a common terminal, and variable means for producing a series opposing coupling between said windings. 120
14. In a wave filter section having impedances in series connection and in shunt connection with respect to the line, a reactive impedance disposed in the one type of connection, and a circuit branch including an inductance disposed on each side of said impedance in the other type of connection, said inductances being inductively coupled in series opposing relation between terminals of said circuit branches on one side of the line, and the impedances of said circuit branches being proportioned to cooperate with the said reactive impedance to permit the free passage of a broad band of wave frequencies through the filter section, while at the same time attenuating waves of all other frequencies. 125

In witness whereof I hereunto subscribe my name this 29th day of December A. D., 1920.

KENNETH S. JOHNSON.
